UNITED STATES PATENT OFFICE.

CARRIE A. FRENCH, OF FORT WORTH, TEXAS.

TOY FIGURE OR DOLL.

SPECIFICATION forming part of Letters Patent No. 729,750, dated June 2, 1903.

Application filed February 25, 1903. Serial No. 144,987. (No model.)

To all whom it may concern:

Be it known that I, CARRIE A. FRENCH, a citizen of the United States, residing at Fort Worth, Texas, have invented certain new and useful Improvements in Toy Figures or Dolls, of which the following is a specification.

This invention relates to a new and useful article of manufacture consisting of toy figures or dolls; and the object is to produce a toy figure or doll which will afford pleasure and amusement and which will serve as an ornament.

Another object is to make use of an article which has heretofore been useless. Egg-shells are generally thrown away or destroyed.

Under this invention egg-shells are used to make an article that has a commercial value.

Other objects and advantages will be fully explained in the following description, and the invention will be more particularly pointed out in the claims.

Reference is had to the accompanying drawings, which form a part of this application and specification.

Figure 1 is a perspective view of a toy man manufactured according to my invention. Fig. 2 is a toy figure of a woman manufactured according to my invention. Fig. 3 illustrates the manner of constructing the bodies of such figures as are shown in Figs. 1 and 2.

Similar characters of reference are used to indicate the same parts throughout the several views.

The bodies of such toy figures as are shown in the drawings consist of an egg-shell A, which is horizontally disposed on a suitable support, the drawings showing a cone-shaped support B, which may be made of pasteboard or other suitable material. For supporting the shell to make a male figure two supports may be used instead of one, as shown in Fig. 1. The head consists of another egg-shell E, poised on the shell A. The shell E is secured on the shell A by means of a small band F of suitable material. The shell A, the collar F, and the shell E may be secured together by suitable paste or glue, and the support B may be secured to the shell A by means of paste or glue. The supports may be further adapted to support the figures in erect position by means of a flat base G, secured to the bottom of the support, as illustrated in Fig. 1. The

figures may be provided with hair, as shown; and faces can be painted on the shells, as illustrated. Much skill may be used to poise the egg-shell for the head in various attitudes to make grotesque or comical figures and to express different emotions characteristic of human beings, and small shells of eggs of different kinds of birds may be made use of also to make comical figures. Egg-shells of different colors will also aid in making different effects in the figures. In preparing egg-shells for such purposes it is preferable to secure shells with as little broken therefrom as possible. Wherever it is practical, a small hole is made in the small end or the end of the shell which is to rest on the horizontal shell for removing the egg therefrom. The figures are completed with any appropriate apparel. The body is tapered with paper K, which is glued or pasted to the shell A and to the support B. A toy figure, with décolleté dress with short sleeves, can be made with good effect. The arms are united to the body A by means of paper P, which is pasted to the body A and to egg-shells H, each of which forms a joint of the arm. The arm and hand is completed with paper P.

Having fully described my invention, what I claim as new, and desire to secure by Letters Patent, is—

1. A toy figure or doll having a body composed of an egg-shell horizontally disposed, a support for said egg-shell, and a head composed of an egg-shell poised on said body.

2. A toy figure or doll having a body consisting of an egg-shell, a support for said body secured to said body, and a head consisting of an egg-shell mounted on said body.

3. A toy figure or doll having a body composed of an egg-shell, a support for said body, a head composed of an egg-shell, and means for securing said head to said body.

4. A toy figure or doll having a head composed of an egg-shell vertically disposed, a body composed of an egg-shell horizontally disposed, means for securing said head on said body, and means for supporting said body.

5. A toy figure or doll comprising an egg-shell having a face painted thereon for a head, an egg-shell forming a body, means for securing said head on said body, and means for supporting said body.

6. A toy figure comprising an egg-shell provided with hair placed thereon and a face painted thereon for a head, an egg-shell constituting a body, means for securing said head on said body, and means for supporting said body.

7. A toy figure or doll comprising an egg-shell having a face painted thereon for a head, an egg-shell forming a body, means for securing said head on said body, means for supporting said body, and arms and suitable apparel placed on said body.

8. A toy figure or doll comprising an egg-

shell for a head, an egg-shell secured to said head for a body, a collar for strengthening said head and body, a support for said body, and arms attached to said body, each arm being composed of paper and one small egg-shell.

In testimony whereof I set my hand, in the presence of two witnesses, this 11th day of February, 1903.

CARRIE A. FRENCH.
